UNITED STATES PATENT OFFICE.

CLIFTON H. BUSICK, OF GOODELL, IOWA.

VALVE-SPRING LIFTER.

Application filed September 23, 1924. Serial No. 739,402.

This invention relates to valve spring lifters generally and particularly adapted for use in compressing the spring to remove the valve in the Ford type of automobile.

One of the objects is to provide a valve spring lifter for maintaining the coil spring under compression while the operator removes the collar retaining pin.

Another object is to provide a construction, wherein the act of compressing the spring automatically rocks the device into such a position that the pivotal point of the lever is moved across the dead center line where it is held until manually displaced.

With these and other objects in view, my invention consists in the novel features of construction, combination and arrangement of parts as will be hereinafter referred to and more particularly pointed out in the specification and claim.

In the accompanying drawing, wherein for the purpose of illustration is shown the preferred embodiment of my invention,—

Figure 1 is a side elevation of the device; 25 Figure 2 is a front view thereof;

Figure 3 is a vertical longitudinal section on the line 3—3 of Figure 2;

Figure 4 is a view similar to Figure 3, but illustrating it in position ready to compress 30 a spring; and

Figure 5 is a transverse section on the line 5—5 of Figure 3.

Referring particularly to the drawing by numerals of reference, 2 designates in dotted lines, the outline of a portion of a gas engine, in which is mounted the valve stem 3 and push rod 4, also shown in outline, the valve stem having at its lower end, the usual collar 5, upon which is seated and confined under compression, the lower end of the coil spring 7.

The device which forms the basis for the present invention is designed for the purpose of compressing the coil spring to permit the removal of the transverse collar retaining pin 18 and thereby the release of the spring and the removal of the valve, and comprises a bifurcated lever 6, the arms 6' of which are pivotally connected at one side 50 of their longitudinal center at 15 with the upper free ends of the arms 8 of a bifurcated strut 9. The lower ends of the arms are bent as at 10 and returned upon themselves to provide legs 11 having at their

upper ends, lateral and inwardly extending, 55 opposed concave shoulders 12, which straddle the push rod 4, while the lower ends of the arms find their support in use, upon the engine frame as shown in Fig. 4. As will be observed particularly upon reference to 60 Figure 5, the legs 11 are joined at their forward portions by a web or bridge 14 which serves to prevent spreading thereof under strain, said bridge being turned outwardly 65 at its lower portion to provide a fulcrum 16 upon which the device as an entirety rocks during the act of compressing and releasing the spring. It should here be remarked that the shoulders 12 serve as positioning means for the lower portion of the device while 70 the concavities therein provide clearance for the collar retaining pin 18 as the device rocks upon the fulcrum 16. The concave shoulders 12 are adapted to straddle the push rod and to keep in engagement with 75 the rod, when the bifurcated lever is moved on the rocking fulcrum.

Pivoted to the inner end or short arm of the lever at 20 is substantially semi-circular cup-shaped yoke 21, the base 22 of which is 80 cut away or recessed at 24 to straddle the lower end of the valve stem, and to provide a flange which engages the under side of the collar 5 to compress the spring. As will be observed, particularly upon reference to 85 Figure 2, the several elements are so arranged that when collapsed, the arms 6' and 8 lie in parallel relation. The outer or free ends of the arms 6' of the lever 6 are connected by a web 26 which serves as a hand 90 or finger piece in operation.

From the foregoing description of the construction of my improved apparatus, it will be seen that I have provided a simple, inexpensive and efficient means for carrying 95 out the objects of the invention, and while I have particularly described the elements best adapted to perform the functions set forth, it is obvious that various changes in form, proportion, and in the minor details of construction may be resorted to, without departing from the spirit or sacrificing any of the principles of the invention.

Having described my invention and the manner of operation throughout the specification, what I claim as new and desire to protect by Letters Patent is:—

A valve spring lifter comprising a bifur-

cated supporting member having a fulcrum on the lower portion thereof, the lower ends of the arms of said supporting member being turned backwardly into parallel relation therewith, inwardly and laterally directed spaced concave shoulders on said backwardly turned portions, a web connecting said back-

wardly turned portions and provided with a rocking fulcrum, a lever pivoted intermediate its length on the upper ends of said supporting member, and a spring lifting yoke on the inner end of said lever.

In testimony whereof I affix my signature.
CLIFTON H. BUSICK.
